UNITED STATES PATENT OFFICE.

JOHN K. KRIEG, OF NEW YORK, N. Y.

DESIGN FOR A PRESS-FRAME.

SPECIFICATION forming part of Design No. 25,884, dated August 4, 1896.

Application filed June 18, 1896. Serial No. 596,076. Term of patent 14 years.

To all whom it may concern:

Be it known that I, JOHN K. KRIEG, a citizen of the United States, residing at New York, in the county and State of New York, have invented and produced a new and original Design for a Press or Machine Frame, of which the following is a specification.

This design relates to frames or supports for presses or machines; and the leading feature of the design consists in a frame having a flat foot from which rise a gooseneck and a horn, said gooseneck having flat-faced lugs at its upper part and a bead at the free part below the lugs, and having its upper edge provided with a nipple, the horn having a nipple at its lower edge, and a rib being extended from the foot along the back of the gooseneck.

The design is illustrated by the accompanying drawings, in which—

Figure 1 is a side elevation of the frame.
Fig. 2 is a front elevation of Fig. 1.

From the flat foot 1 rises a gooseneck 2 3 4

and a horn 5 6. The gooseneck has at its upper part flat-faced lugs 7 and a bead 8 at 25 the free part below the lugs. At the upper edge of the gooseneck is a nipple or lug 9. At the lower edge of the horn is a nipple or lug 10. A rib 11 is extended from the foot along the back of the gooseneck. The lugs 30 7 are shown provided with eyes 12 and the horn part 6 has an eye 13. The inner edges of the gooseneck and horn form a continuous oval-like outline 14, 15, 16, 17, and 18.

What I claim as new, and desire to secure 35 by Letters Patent, is—

The design for a machine-frame substantially as shown and described.

In testimony whereof I have hereunto set my hand in the presence of two subscribing 40 witnesses.

JOHN K. KRIEG.
